UNITED STATES PATENT OFFICE.

ROY W. CATCHING, OF FAIRVIEW, MONTANA.

SELF-DUMPING BUCKET.

1,079,744.

Specification of Letters Patent. Patented Nov. 25, 1913.

Application filed June 18, 1913. Serial No. 774,370.

To all whom it may concern:

Be it known that I, ROY W. CATCHING, a citizen of the United States, and a resident of Fairview, in the county of Dawson and State of Montana, have made certain new and useful Improvements in Self-Dumping Buckets, of which the following is a specification.

My invention is an improvement in self dumping buckets and has for its object to provide a bucket of the character specified, especially adapted for use in concrete work, and wherein the bucket and the dumping doors are both connected with the hoisting cable, in such manner that while the bucket and its contents are suspended during the transportation or hoisting, the weight of the bucket and the material in the bucket will hold the dumping doors closed, the said doors being at such time directly connected with the hoisting mechanism, and wherein means is provided for clamping the bucket to the hoisting mechanism, after the bucket has reached the place of disposal and has been lowered to such place of disposal, to cause the bucket to move relatively with respect to the dumping doors, whereby to dump the load.

In the drawings:—Figure 1 is a side view of the improved bucket with the dumping mechanism in section, and showing said mechanism in dumping position, Fig. 2 is a similar view showing the bucket in loading position, Fig. 3 is a side view of the latch mechanism, Fig. 4 is a section on the line 4—4 of Fig. 1, Fig. 5 is a perspective view of the latch plate, Fig. 6 is a perspective view of the support for the latch plate, and, Fig. 7 is a side view of the trip mechanism detached.

The present embodiment of the invention is shown in connection with a cylindrical bucket comprising a body 1 and sectional doors 2, the said doors being hinged to the body at the lower end thereof, and at diametrically opposite points, as indicated at 3, and the said doors when in closed position have their inner straight edges abutting, as shown in Fig. 2.

Each end of the bucket is provided with a reinforcing band 4, and the hinges are secured to the lower band and to the body of the bucket. The bucket is provided with bails 5, the said bails being 3 in number, and each bail is connected at its lower end to the upper end of the bucket, as indicated

at 6, and at its upper end to a sleeve or casing, as indicated at 7.

The casing 8 is hollow, and the upper end thereof is provided with an opening 9 for a purpose to be presently described, while the lower end is flaring or frusto-conical as indicated at 10. The lower end of the casing is closed by a plate or disk 11, provided at its center with an opening 12 registering with the opening 9 of the casing, and at its periphery with openings 13, for receiving threaded stems 14 depending from the lower end of the casing 8. Nuts 15 are engaged with the stems, for holding the plate in place, and a rod or cylindrical bar 16 passes through the registering openings 9 and 12, and extends above and below the said casing.

A latch plate is supported by the casing and the disk 11, the said plate being in the form of a disk 17, having a central opening 18 registering with the openings 9 and 12, but of larger size than the said opening, and the rod or bar 16 before mentioned passes through the said opening 18 of the latch plate. The latch plate is also provided with a radial lug 19, and the said lug is received in an opening 20 at the lower end of the casing 8, the said opening being a notch in the lower end of the portion 10 of the said casing. The engagement of the lug with the opening 20 provides a hinged connection between the latch plate and the casing, and a coil spring 21 is arranged between the latch plate and the supporting plate 11, the said spring acting normally to press the latch plate upward. The lower end of the spring is seated in a recess 22 in the upper face of the supporting plate 11, and a spacing or limiting lug 23 is provided on the upper face of the said plate 11, for limiting the downward movement of the latch plate, with respect to the supporting plate 11. It will be noted that the spring 21 normally holds the latch plate in the position of Fig. 1, that is in a position to cause the sides of the opening 18 of the said latch plate to grip the periphery of the rod or bar 16, to prevent movement of the said bar with respect to the latch plate. The lug 23 limits the downward movement of the latch plate to a position approximately parallel with the upper face of the plate 11. The lug 19 supports the hinged edge of the latch plate slightly above the upper face of the plate 11, and the lug 23 is provided for supporting the opposite side.

A tripping lever is provided for pressing the free edge of the latch plate downward against the resistance of the spring 21 to release the rod 16, and the said lever 24 is pivoted in an opening 25 in the wall of the casing 8, by means of a pivot pin 26. The outer end of the lever is provided with an eye 27 for engagement by a flexible member to operate the lever, and the inner end is provided with a lug or nose 28 for engaging the upper face of the latch plate at the spring 21 to depress the said plate. The lower end of the rod 16 is provided with an eye 29, and the eye is engaged by one end of a chain 30.

Chains 31 are connected to the doors 2, each chain having one of its ends connected to an eye 32 on the inner face of the door, and the other end of each of the chains 31 is connected to the lower end of the chain 30. It will be evident that when the rod or bar 16 is moved upwardly, the doors will be closed, as shown in Fig. 2, and the doors are held in such position, by means of the chains.

A stop 33 is connected to the rod or bar 16 at its lower end, the said stop being approximately pear-shaped, and arranged with its small end upward. The vertical opening 34 of the stop through which the rod 16 passes is flaring at its lower end, as shown, and the stop is secured to the rod or bar by means of a cross pin 35, in such position that the flaring end of the opening is at the upper end of the chain 30. The upper end of the rod 16 is provided with a cross head 36, and the lifting rope 37 for the bucket is connected with an eye 38 on the rod or bar above the cross head. The end of the rope is passed through the eye, and a clamp 39 is utilized for securing the said end to the body of the rope. The ends of the cross head are provided with openings through which are passed eye-bolts 40, from below upward, and each bolt is engaged by a nut 41 above the cross head. Coil springs 42 are engaged at one end with the eye-bolts, and at the other with perforated lugs 43 which extend upward from enlargements 44 on the flaring portion 10 of the casing 8. The springs normally hold the casing in elevated position, and also tend to hold the bucket in elevated position.

The improved bucket is especially designed for use with concrete or the like, and is so arranged that the dumping mechanism may be operated with a single line, and may be operated to dump under water or in the open air without the services of an extra man, and with the single line. The said line is connected with the eye 27 of the lever 24.

The dumping mechanism may be used in connection with any construction of bucket, the form shown being so shown as a type of

bucket with which the dumping mechanism may be used.

In operation, as for instance in concrete work, the bucket is first filled at the mixer, and after it has been filled, the operator operates the trip lever 24, and at the same time signals to the operator in charge of the hoisting mechanism to raise the bucket. The cable 37 as it is wound up draws up the rod or bar 16 and takes up any slack that there may be in the chains 30 and 31. The drawing up of the bar or rod 16 places the springs 24 under tension, and holds the sections of the bottom tightly in place. The bucket can now be lowered to the place of disposal and may be set down on a supporting surface, so that the entire weight of the bucket is taken from the lifting cable. The cable 37 is now given more slack and the bar or rod 16 moves into the position of Fig. 1, the latch plate offering no resistance to the downward movement of the said rod or bar. The said latch plate, however, prevents upward movement of the bar, and to dump it is only necessary to again wind up the cable 37. The casing 8—10 is now clamped to the rod or bar 16, and the bucket is lifted, with the chains 30—31 slack, so that the contents of the bucket force the door sections open, and the said contents are dumped. The bucket may be returned to the filling position either open or shut, as may be desired.

I claim:

1. In combination with the bucket having an open bottom, and doors hinged to the side wall of the bucket for closing the bottom, said doors consisting of similar sections, a casing arranged above the bucket, bails connecting the casing to the bucket, said casing having a central vertical opening, a rod or bar slidable through the opening of the casing, chains connecting the lower end of the rod or bar to the sections of the door, for closing the said sections when the rod or bar is moved upward with respect to the casing, said rod or bar having means at its upper end for connection with a hoisting cable, a latch plate within the casing and hinged at one side thereof and having a central opening through which the rod extends, a spring between the plate and the bottom of the casing and normally holding the said latch plate in inclined position with respect to the rod to cause the sides of the opening of the plate to grasp the rod, said casing having an opening in its side wall at the opposite side to the hinged connection of the latch plate, a trip lever pivoted in the opening and having a nose for engaging and depressing the latch plate into a position perpendicular to the axis of the bar or rod, a stop in the casing for limiting the downward movement of the latch plate, a stop on the lower end of the rod or bar for engaging

- the bottom of the casing to limit the upward movement of the said rod or bar, a cross head rigidly connected with the casing at its upper end and extending on opposite sides thereof, and a coil spring connecting each end of the said cross head with the casing.
2. In combination with the bucket having an open bottom, and doors hinged to the side wall of the bucket for closing the bottom, said doors consisting of similar sections, a casing arranged above the bucket, bails connecting the casing to the bucket, said casing having a central vertical opening, a rod or bar 15 slideable through the opening of the casing, chains connecting the lower end of the rod or bar to the sections of the door, for closing the said sections when the rod or bar is moved upward with respect to the casing, said rod or bar having means at its upper end for connection with a hoisting cable, a latch plate within the casing and hinged at one side thereof and having a central opening through which the rod extends, 20 said rod or bar having means at its upper end for connection with a hoisting cable, a latch plate within the casing and hinged at one side thereof and having a central opening through which the rod extends, a spring between the plate and the bottom of the casing and normally holding the said latch plate in inclined position with respect to the rod to cause the sides of the opening of the plate to grasp the rod, said casing 25 having an opening in its side wall at the opposite side to the hinged connection of the latch plate, a trip lever pivoted in the opening and having a nose for engaging and depressing the latch plate into a position 30 perpendicular to the axis of the bar or rod, a cross head rigidly connected with the casing at its upper end and extending on opposite sides thereof, and a coil spring connecting each end of the said cross head with the casing.
3. In combination with the bucket having an open bottom, and doors hinged to the side wall of the bucket for closing the bottom, said doors consisting of similar sections, a 35 casing arranged above the bucket, bails connecting the casing to the bucket, said casing having a central vertical opening, a rod or bar slideable through the opening of the casing, chains connecting the lower end of the rod or bar to the sections of the door, for closing the said sections when the rod or bar is moved upward with respect to the casing, said rod or bar having means at its upper end for connection with a hoisting cable, a latch plate within the casing and hinged at one side thereof and having a central opening through which the rod extends, 40 a spring between the plate and the bottom of the casing and normally holding the said latch plate in inclined position with respect to the rod to cause the sides of the opening of the plate to grasp the rod, said casing having an opening in its side wall at the opposite side to the hinged connection of the latch plate, and a trip lever pivoted in the opening and having a nose for engaging and depressing the latch plate into a position 45 perpendicular to the axis of the bar or rod.
4. In combination with the bucket having an open bottom, and doors hinged to the side wall of the bucket for closing the bottom, said doors consisting of similar sections, a 50 casing arranged above the bucket, bails connecting the casing to the bucket, said casing having a central vertical opening, a rod or bar slideable through the opening of the casing, chains connecting the lower end of the rod or bar to the sections of the door, for closing the said sections when the rod or bar is moved upward with respect to the casing, said rod or bar having means at its upper end for connection with a hoisting cable, a latch plate within the casing and hinged at one side thereof and having a central opening through which the rod extends, a spring between the plate and the bottom of the casing and normally holding the said latch plate in inclined position with respect to the rod to cause the sides of the opening of the plate to grasp the rod, said casing 55 having an opening in its side wall at the opposite side to the hinged connection of the latch plate, and a trip lever pivoted in the opening and having a nose for engaging and depressing the latch plate into a position perpendicular to the axis of the bar or rod.
5. In combination with the bucket having an open bottom, and doors hinged to the side wall of the bucket for closing the bottom, a rod above the bucket having at its upper end means for connection with hoisting mechanism, flexible connections between the lower end of the rod and the doors, a sleeve slideable on the rod and rigidly connected with the bucket, a latch plate hinged to the sleeve and having an opening through which the rod passes, a spring normally holding the latch plate in inclined position with respect to the axis of the rod to cause the sides of the opening to grip the rod to clamp the rod to the sleeve, a lever pivoted to the sleeve and having a lateral lug for engaging the latch plate to move the sleeve into a position at right angles to the axis of the rod to release the rod when the lever is swung, a cross head rigid with the upper end of the rod, and springs connecting the ends of the cross head with the sleeve and acting normally to draw the sleeve toward the upper end of the rod.
6. In combination with the bucket having an open bottom, and doors hinged to the side wall of the bucket for closing the bottom, a rod above the bucket having at its upper end means for connection with hoisting mechanism, flexible connections between the lower end of the rod and the doors, a sleeve slideable on the rod and rigidly connected with the bucket, a

ing and having a nose for engaging and depressing the latch plate into a position perpendicular to the axis of the bar or rod, and a yielding connection between the bar and the casing for normally pressing the said bar upward.

7. In combination with the bucket having an open bottom, and doors hinged to the side wall of the bucket for closing the bottom, said doors consisting of similar sections, a 75 casing arranged above the bucket, bails connecting the casing to the bucket, said casing having a central vertical opening, a rod or bar slideable through the opening of the casing, chains connecting the lower end of the rod or bar to the sections of the door, for closing the said sections when the rod or bar is moved upward with respect to the casing, said rod or bar having means at its upper end for connection with a hoisting cable, a latch plate within the casing and hinged at one side thereof and having a central opening through which the rod extends, a spring between the plate and the bottom of the casing and normally holding the said latch plate in inclined position with respect to the rod to cause the sides of the opening of the plate to grasp the rod, said casing 80 having an opening in its side wall at the opposite side to the hinged connection of the latch plate, and a trip lever pivoted in the opening and having a nose for engaging and depressing the latch plate into a position perpendicular to the axis of the bar or rod.
8. In combination with the bucket having an open bottom, and doors hinged to the side wall of the bucket for closing the bottom, a rod above the bucket having at its upper end means for connection with hoisting mechanism, flexible connections between the lower end of the rod and the doors, a sleeve slideable on the rod and rigidly connected with the bucket, a latch plate hinged to the sleeve and having an opening through which the rod passes, a spring normally holding the latch plate in inclined position with respect to the axis of the rod to cause the sides of the opening to grip the rod to clamp the rod to the sleeve, a lever pivoted to the sleeve and having a lateral lug for engaging the latch plate to move the sleeve into a position at right angles to the axis of the rod to release the rod when the lever is swung, a cross head rigid with the upper end of the rod, and springs connecting the ends of the cross head with the sleeve and acting normally to draw the sleeve toward the upper end of the rod.
9. In combination with the bucket having an open bottom, and doors hinged to the side wall of the bucket for closing the bottom, a rod above the bucket having at its upper end means for connection with hoisting mechanism, flexible connections between the lower end of the rod and the doors, a sleeve slideable on the rod and rigidly connected with the bucket, a

latch plate hinged to the sleeve and having an opening through which the rod passes, a spring normally holding the latch plate in inclined position with respect to the axis of the rod to cause the sides of the opening to grip the rod to clamp the rod to the sleeve, a lever pivoted to the sleeve and having a lateral lug for engaging the latch plate to move the same into a position at right angles to the axis of the rod to release the rod when the lever is swung, and a spring normally pressing the sleeve toward the upper end of the rod.

7. In combination with the bucket having an open bottom, and the doors hinged to the bucket for closing the bottom, a rod above the bucket having at its upper end means for connection with hoisting mechanism, flexible connections between the lower end of the rod and the doors, a sleeve slidable on the rod and rigidly connected with the bucket, a latch plate hinged to the sleeve and having an opening through which the rod passes, a spring normally holding the latch plate in inclined position with respect to the axis of the rod to cause the sides of the open-

ing to grip the rod to clamp the rod to the sleeve, trip mechanism in connection with the sleeve for moving the latch plate perpendicular to the axis of the rod to release the rod from the sleeve, and a yielding connection between the rod and the sleeve and acting normally to move the sleeve toward the upper end of the rod.

8. In combination with the bucket having an open bottom, and the doors hinged to the bucket for closing the bottom, a rod above the bucket having at its upper end means for connection with hoisting mechanism, flexible connections between the lower end of the rod and the doors, a sleeve slidable on the rod and rigidly connected with the bucket, normally operative means for clamping the rod to the sleeve, trip mechanism for releasing the clamping mechanism, and a yielding connection between the rod and the sleeve for moving the sleeve toward the upper end of the rod.
